UNITED STATES PATENT OFFICE

2,000,447

ELECTRIC SWITCH

Arthur A. Johnson, New Bedford, Mass., assignor
to John I. Paulding, Inc., New Bedford, Mass.,
a corporation of Massachusetts

Application December 19, 1929, Serial No. 415,342

2 Claims. (Cl. 173—346)

My invention relates to electric switches and is exemplified in a switch for electric lamps of the key type.

The main object of the invention is the provision of a switch of simple and efficient construction which may be assembled rapidly and at a low cost.

Other objects of the invention will be more specifically pointed out and described herein-after.

My invention contemplates a switch structure comprising a cam member having an inclined cam portion of such form that when the cam member is rotated the inclination of said cam portion is reversed whereby a rocker member is operated to close or break a circuit by engagement with or separation from suitable contacts. In the preferred form of the invention, the cam member is made in the form of a spindle having a cam portion inclined to its longitudinal axis so that when the spindle is rotated on said axis through an arc of one hundred and eighty degrees, said cam portion is reversed in inclination.

In the drawing illustrating one form of the invention, Figure 1 is a vertical central sectional view of an electric lamp socket adapted to be operated in accordance with my invention showing the rotary cam member in elevation; Fig. 2 is a central sectional view on line 2—2 in Fig. 1 looking from right to left; Fig. 3 is a cross-sectional view on line 3—3 in Fig. 1 looking upwardly and showing the switch mechanism in elevation; Fig. 4 is a bottom end view of the fixture; Fig. 5 is a top plan view of the insulating body, one of the fixed contacts being omitted to show the form of recess therefor; Fig. 6 is a sectional view on line 6—6 in Fig. 5 showing the means for fastening the screw shell to the insulating body; Fig. 7 is a detail sectional view on line 7—7 in Fig. 5; Fig. 8 is a detail sectional view on line 8—8 in Fig. 3; Fig. 9 is a plan view of the insulating disk for closing the chamber in the insulating body looking downwardly in Fig. 1; and Fig. 10 is a side elevation of the actuating spring.

In the drawing, the switch of my invention is shown as applied to an electric lamp socket but this is merely illustrative since it may be used in various other types of electric fixtures and my invention is not to be limited to that particular use.

Referring to the drawing, the lamp socket shown which may be of any suitable type such as is shown and described in United States Letters Patent to Frank E. Johnson, No. 1,586,367, issued May 25, 1926, comprises a cap portion 10 having

the usual bushing 12 for attachment to the nipple of an electric fixture and a shell portion 14 provided with a key slot 16. Within the cap and shell is mounted respectively insulating linings 17 and 18. An insulating body 20 carries the switch mechanism and has attached thereto a screw shell 22 for receiving the threaded portion of an electric lamp, these parts being mounted within the shell of the socket.

The insulating body 20 is provided in its lower face with an open rectangular recess or chamber 24 having a central sub-recess 26 within which recesses is mounted the switch mechanism. Interposed between the screw shell and lower face of the insulating body and covering the recess or chamber 24, is a disk 27 of fibre or other insulating material carrying a contact member 28, one end of which is turned over on the lower side of the disk as a free end to serve as a lamp contact 30 and the other end of which is turned through a slot 31 in the disk and provided on one side with an upturned contact member 32 which projects into the recess 24. The body portion of the contact member is secured to the disk by a lug 34 on each side thereof which is turned through a suitable hole 35 in the disk and clamped on the upper side thereby for holding the contact member fixed firmly to the disk. The latter and the screw shell are secured to the insulating body by two screws 36 and 37 mounted in suitable bores in the insulating body and holes 38 in the disk, the first having its upper end threaded through a square nut 39 set in a square recess 40 in the upper face of the insulating body and the second threaded into a right-angled terminal member 41 carrying a binding screw 42 to which may be connected one of the wires or conductors 43 (Fig. 6). Suitable washers 44 may be interposed between the heads of the screws and the inturned ears 45 of the base of the screw shell. The terminal 41 is fastened in position on a shelf in an outer recess 47 formed in the insulating body and is connected to the screw shell. Set in a similar outer recess 50 on the other side of the insulating body is a right-angled terminal plate 51 carrying a binding screw 53 for the connection of the other wire 54 of the circuit thereto; said terminal plate being connected by a screw 56 to the square butt 57 of a fixed contact 58 extending into the chamber 24.

Mounted within the recess 24 and the recess 26 is a switch mechanism constructed in accordance with my invention and comprising a rotary cam member 60 a rocker member 62 and an actuating spring 64 (Figs. 1 and 2). The rotary cam member is in the form of a spindle designated as 60

having approximately midway its length a cam portion 66 which is inclined to the longitudinal axis of the spindle and which is formed by bending that portion of the spindle laterally, the cam portion being connected at its two ends to the spindle by oppositely inclined portions 67 and 68 respectively. The cam portion is preferably so formed that its longitudinal axis and the longitudinal axes of the portions 67 and 68 lie in a plane which passes through the longitudinal axis of the main portions of the spindle. The upper and lower surfaces of the cam portion as shown in Fig. 1 may be flattened to form cam surfaces to be engaged by the rocker member. The latter member is preferably stamped out of sheet material and is flat and U-shaped in plan having its two ends 70 extended outwardly in a lateral direction in order to engage the fixed contacts 32 and 58. The outer edge of the head of the rocker member is provided with two recesses thereby forming a central projecting lug 72 around which is received one end of the actuating spring 64 of helical form having its other end abutting the bottom of the sub-recess, the sub-recess being formed to hold that end of the spring against lateral movement while permitting a slight pivotal movement of the spring in the operation of the rocker member (Figs. 1 and 2). The free end of the spindle is mounted in a hole 14 formed in the insulating body and its other end is held in position at the bottom of a groove 75 by a small piece 76 fitting in suitable grooves 77 which is held in place by the disk 27. Upon the outer end of the cam member is mounted a key 78 for turning it to open and close the switch.

In order to insure a rapid and instantaneous break between the fixed contacts and the rocker member when the latter is operated to break the circuit, the two ends 80 and 81 of the actuating spring 64 are closed, so that the planes of said ends are approximately perpendicular to the central axis of the spring, and the floor of the sub-recess 26 is oblique, being slanted toward the fixed contacts as shown in Fig. 1. As a result of this construction, when the actuating spring is compressed by the initial turning of the cam member and before the latter has been turned into a position permitting the rocker member to be rocked away from the contacts, the entire force of the spring acts in a direction to hold the rocker member in tight engagement with the fixed contacts. When the cam member has been rotated to a point which permits the rocker member to move, it is then snapped away from the fixed contacts instantaneously thereby preventing arcing. The elimination of arcing is important because it prevents burning or fusing of the contacts and enables the switch to carry a greater load.

The operation of the switch is easily understood. In Figs. 1 and 2 the switch is shown in closed position with the two ends 70 of the rocker member 62 in engagement with the fixed contacts 32 and 58 thereby bridging the space between said two contacts and closing the circuit for lighting a lamp mounted in the screw shell. In this position, the actuating spring 64 being under compression forces the rocker member down into the valley formed by the junction of the top cam surface of the cam portion 66 with the oppositely inclined portion 67 and holds it there. To open the circuit, the spindle 60 is turned through an arc of one hundred and eighty degrees by the manipulation of the key 78. In this operation the rocker member is raised, thereby compressing the actuating spring and

when the spindle has been turned sufficiently to present the opposite cam surface of the cam portion 66 to the rocker member, the spring then forces the rocker member down that inclined surface causing it to be rocked to the other side of the recess away from the fixed contacts and to come to rest in the valley formed by the junction of the cam portion 66 with the inclined portion 68, the pressure exerted by the spring tending to lock the rocker member in the valley. To turn the spindle to open or close the circuit requires the exertion of a slight force to raise the rocker member against the compression of the spring and when the spindle has been partially turned, the pressure of the spring will cause the rocker member to be rocked and the remaining movement of the spindle through its arc of one hundred and eighty degrees to be completed automatically. Although the rocker member is loosely mounted on the cam member, any lateral movement thereof is prevented by engagement between the sides of the rocker member and the side walls of the recesses in the insulating body (Fig. 2).

The assembling of the parts is simple and can be accomplished expeditiously since the switch parts do not require to be fastened within the insulating body but may be placed in the recesses in their normal relation, the end of the cam member being inserted in the hole in the insulating body and its main portion being forced down into the groove after which the small piece 76 is inserted in the groove 77, the disk 27 placed in position with the screw shell and secured to the insulating body by the two screws 36 and 37, the terminal plate 51 and contact member 58 having previously been fastened to the insulating body by the screw 56. The assembling of the entire structure requires, therefore, the manipulation of only three screws and therefore can be accomplished in a most expeditious manner.

It will be observed that my switch is extremely simple in construction comprising but three main elements which are loosely mounted in the insulating body and held in normal operative position at all times by their relations to each other and by the form of the recesses and the attachment to the insulating body of the disk and screw shell. Because of this simple construction, the switch mechanism is positive in operation, durable and will last throughout the life of the actuating spring.

It is to be understood that the form of the invention shown and described herein is merely illustrative of the invention and that it is not to be limited to the particular form shown since it may be embodied in other forms within the scope of the following claims.

What I claim is:—

1. An electric switch comprising a recessed insulating body, a pair of fixed contacts mounted in separated relation in said recess, a rotary spindle having an inclined cam portion adapted to be reversed in inclination by the rotation of said spindle, a U-shaped rocker member loosely mounted on and straddling the cam portion of said rotary spindle, an actuating spring for holding said rocker member in engagement with said rotary spindle, said spring having closed ends, one abutting said rocker member and the other the bottom of said recess and said bottom being in a plane perpendicular to the plane of the contacting surfaces of said fixed contacts to prevent arcing when the engagement between the rocker

member and said contacts is broken by the operation of the rotary spindle.

2. An electric switch comprising a recessed insulating body, a pair of fixed contacts mounted in said recess, a rotatable spindle mounted in said recess transversely thereof, said spindle being bent midway to form an inclined cam portion having a valley at each end, a U-shaped rocker member straddling said cam portion in reversed position and a helical spring under compression having one end seated on the floor of said recess and the other end engaging the head of said rocker member to hold it in constant engagement

5 with said cam portion and to move it thereon from one valley to the other whenever said spindle is rotated in order to rock the free ends of said rocker member into and out of bridging engagement with said fixed contacts, the floor of said recess being oblique to the transverse axis of said insulating body and perpendicular to the plane of the contacting surfaces of said fixed contacts to prevent arcing when the engagement between the rocker member and said contacts is 10 broken by the operation of said rotatable spindle.
